Primary Examiner — Kendra Leslie Hamilton
Assistant Examiner — Elizabeth S Struble

(74) *Attorney, Agent, or Firm* — Foley & Lardner LLP(57) **CLAIM**

The ornamental design for a sample collection device as shown and described.

DESCRIPTION

FIG. 1 is a top, rear, left side perspective view of a sample collection device;

FIG. 2 is a bottom, rear, right side perspective view thereof;

FIG. 3 is a top plan view thereof;

FIG. 4 is a bottom plan view thereof;

FIG. 5 is a right side elevation view thereof;

FIG. 6 is a left side elevation view thereof;

FIG. 7 is a front elevation view thereof; and,

FIG. 8 is a rear elevation view thereof.

In the drawings, broken lines formed by equal length dashes depict portions of the sample collection device that form no part of the claimed design.
